Primary Examiner—James M. Gandy*Assistant Examiner*—Robin V. Taylor*Attorney, Agent, or Firm*—Donald W. Erickson[57] **CLAIM**

The ornamental design for a brush holder, as shown and described.

DESCRIPTION

FIG. 1 is a perspective view of my brush holder showing my new design;

FIG. 2 is a top plan view thereof, the bottom side being identical therewith;

FIG. 3 is a side elevational view, right side, thereof;

FIG. 4 is a side elevational view, left side, thereof; and,

FIG. 5 is an end view thereof, the other end being identical.

The broken line showing of a paint can is for illustrative purposes only and forms no part of the claimed design.

FIG. 1

FIG. 2

FIG. 3

FIG. 4

FIG. 5
